UNITED STATES PATENT OFFICE.

JULIUS A. PEASE, OF NEW YORK, N. Y.

IMPROVEMENT IN SHIRT-COLLARS.

Specification forming part of Letters Patent No. 38,909, dated June 16, 1863.

To all whom it may concern:

Be it known that I, JULIUS A. PEASE, of the city, county, and State of New York, have invented a new and Improved Shirt-Collar; and I do hereby declare that the following is a full and exact description of the same, reference being had to the accompanying drawings, and to the letters of reference marked thereon.

The nature of my invention consists in making a shirt-collar that needs only to be wiped with a wet towel or sponge to be ready for use and that will not break down by wearing.

To enable others skilled in the art to make and use my invention, I will proceed to describe its construction and operation.

Figure 1 is a perspective view of the collar. Figs. 2 and 3 are sectional views.

I make my frame *c*, Fig. 3, of steel or other

metal, and of the size I want my collar. I cover said frame with water-proof enameled cloth or other enameled material, or I cover the said frame with cloth and enamel it afterward. The frame *c* is for the purpose of preventing the breaking down of the collar by use. To have a clean collar, it is only necessary to wipe it with a wet towel or sponge.

What I claim as my invention, and desire to secure by Letters Patent, is—

A shirt-collar made by covering a metal frame with water-proof enameled cloth or other material, substantially as before described.

JULIUS A. PEASE.

Witnesses:

EDWARD DEMMING,
CHARLES C. BILLINGS.
